BILLBOARD

Filed Oct. 4, 1924

Inventor:

Warren Kelley,
by Spear, Middleton, Donaldson & Hull
Atty.

UNITED STATES PATENT OFFICE.

WARREN KELLEY, OF BALTIMORE, MARYLAND.

BILLBOARD.

Application filed October 4, 1924. Serial No. 741,740.

To all whom it may concern:

Be it known that I, WARREN KELLEY, a citizen of the United States, and resident of Baltimore, Maryland, have invented certain new and useful Improvements in Billboards, of which the following is a specification.

The object of the invention is to provide a billboard of simple, light, and durable construction.

A further object is to provide for the relief of wind pressure imposed upon the board during the prevalence of high winds and to provide a structure which will be well ventilated and will dry off quickly in wet weather, it being understood that the structure is intended primarily for outdoor use, though not limited to such use.

In the accompanying drawings—

Figure 1 is a front view of the billboard embodying my invention.

Fig. 2 is a vertical sectional view on the line 2—2 of Fig. 1.

Fig. 3 is an enlarged detail view in vertical section of a portion of the structure.

Fig. 4 is an enlarged detail view in horizontal section on the line 4—4 of Fig. 1.

1 indicates the sign carrying board which is preferably made of thin sheet metal. At 30 its upper and lower edges the board has connected to it a pair of angles 2 which extend along the whole length thereof and serve as reinforcing means as well as means for connecting the billboard to transverse metal strips 3, located at intervals along 35 the length of the structure and fastened to the frame thereof. At top and bottom the billboard is carried beyond the alignment of the angle flanges and bent over as shown at 40 4. At the top of the board the transverse metal strips 3 serve as hangers and at the bottom they serve as means for attachment of the lower part of the billboard.

The angle irons are spaced apart slightly 45 from the transverse strips and are connected thereto by adjusting bolts by means of which the billboard may be firmly held. The transverse members 3 are nailed or screwed to the longitudinal wooden beams or stringers 5 of which there are two at top 50 and two at the bottom. The beams 5 are

bolted at their ends to the vertical posts 6. The moulding strips 7 and 8 are nailed to the beams 5.

The vertical posts 6 are reinforced at intervals from top to bottom by cross pieces with angle reinforcements 9 and are supported at their lower end by the foundation structure which rests upon or is embedded in the ground. This structure consists of 60 base board 10 at each end upon which the vertical posts 6 rest reinforced by braces 11 and longitudinal beams 12.

Free passage of the wind through wind spaces 13 Fig. 2 is allowed by this construction at the upper and lower edges of the board. At the sides wind space is provided by employing a board shorter than the distance between the end posts, these spaces being marked 14.

It will be seen from the above that while a thin light main board is employed it is suspended in such a manner relative to the frame that it will be protected against damage from wind pressure and from collection of moisture. Provision is made for the free circulation of air past its edges relieving it of wind pressure, providing for quick drainage of rain water from the board and for its rapid drying.

The end posts extend up on the inner sides of the upper and lower beams and the space between them is enclosed by sheet metal finishing pieces 15.

It will be observed that the billboard has 85 a display surface on each side.

I claim:

1. In combination, a billboard and a frame for supporting the same, comprising a pair of beams at the top of the board and 90 a pair of beams at the bottom of the board, the members of each pair being spaced apart for air circulation and having the edge of the board located between them and spaced apart from them, and cross members for 95 supporting the board from said beams.

2. In combination in a billboard frame, pairs of horizontal spaced apart beams at top and bottom, transverse metal strips spanning the space between each pair of 100 beams, angle irons connected to the upper and lower edges of the billboard, and bolts

for connecting the angle irons with the transverse strips in spaced apart relation for drawing the board into position.

3. In combination, a billboard, a supporting frame therefor, comprising a pair of horizontal beams at the top of the board and a pair of beams at the bottom of the board, the beams of each pair being spaced apart and means

for supporting the billboard from said beams in spaced apart relation thereto, said means being adjustable to draw said billboard into position, and means for supporting the beams.

In testimony whereof, I affix my signature.

WARREN KELLEY.
